The ornamental design for a display rack, as shown and described.

DESCRIPTION

FIG. 1 is a front perspective view of a display rack showing our new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a cross-sectional view taken along line 9-9 in FIG. 3.

The small circles that appear on the entire surface of the display rack are through holes. The broken line hatching shown in the cross-sectional view of FIG. 9 forms no part of the claimed design.
